United States Patent

Des. 241,380
Patented Sept. 7, 1976

241,380

PORTRABLE DISPLAY CASE

Leo Graviner, 1 Woodhue Court,
Baltimore, Md. 21207

Filed July 2, 1974, Ser. No. 485,241

Term of patent 14 years

Int. Cl. D3—02

U.S. CL. D87—1 R

FIG. 1

FIG. 3

FIG. 2

FIG. 4

FIG. 1 is a front perspective view of a portable display case showing my new design in open position;

FIG. 2 is a front perspective view thereof with the top tray portion in another position;

FIG. 3 is a front perspective view with the top tray in still another position; and

FIG. 4 is a rear perspective view of the portable display case in open position.

I claim:

The ornamental design for a portable display case, substantially as shown and described.
